UNITED STATES PATENT OFFICE

WILLIAM G. KENDALL, OF NEWARK, NEW JERSEY

COMPACT-HOLDING RING FOR VANITY CASES

Application filed May 4, 1928. Serial No. 275,170.

This invention relates to vanity cases, and particularly to an improved compact holding ring, the object being to provide an improved construction wherein the compact may be readily inserted and resiliently held in place.

Another object of the invention is to provide a compact holding ring substantially L-shaped in cross section with a shoulder formation for engaging part of a compact plate for holding the same in place.

A still further object of the invention is to provide a compact plate holding ring wherein improved spaced fingers are used to resiliently hold the compact plate in position; the fingers being so arranged that an implement may be placed therebetween for ejecting the plate at any time.

In the accompanying drawings—

Fig. 1 is a plan view of the vanity case shown open and shown provided with the compact plate holding ring embodying the invention.

Fig. 2 is a sectional view through Fig. 1 approximately on the line 2—2, the same being on an enlarged scale.

Fig. 3 is an enlarged perspective view of the ring shown in Fig. 1.

Fig. 4 is a fragmentary perspective view of a ring disclosing a slightly modified construction to that illustrated in Fig. 3.

Referring to the accompanying drawings by numeral, 1 indicates the body of the vanity case and 2 the cover. The cover 2 is connected to body 1 by suitable hinge 3, whereby the vanity case may be opened and closed as desired. Arranged interiorly of the body 1 is a compact plate holding ring 4 which may be held in place in any desired manner, as for instance by ring 5. A holding ring as illustrated particularly in Figs. 2 and 3 presents an annular ring structure having a tubular portion or body 6 and radiating horizontal flange 7, whereby a substantially L-shaped structure is presented in cross section.

Preferably the flange 7 is solid throughout in order to present a pleasing appearance to the eye, while the tubular portion or body 6 is provided with a number of slots or notches 8, whereby a plurality of resilient sections 9 are presented. Each of these sec-

tions is provided with a groove 10. In forming groove 10, the edge 11 presents a shoulder against which the upper part of the annular projection 12 presses when the parts are in opposite position as shown in Fig. 2. Preferably, the sections 9 extend slightly inwardly, whereby, when the compact plate 13 is forced into position as shown in Fig. 2, these sections will be slightly spread, and will yield sufficiently to permit the projecting portion 12 to snap into the respective grooves 10. It is of course evident that the entire ring 4 is of very thin material, and is more or less resilient throughout, so that there is no difficulty in forcing the compact plate into position.

Ordinary friction would probably hold the plate in place if the parts were not jarred, but as vanity cases are turned over and jarred many times, the groove 10 with the containing shoulder 11 is very desirable, and acts substantially as a locking means for locking the compact plate in position. When it is desired to remove the plate, the vanity case may be turned over and the edge struck sharply on a table or support, whereupon the plate will drop out.

If the spring action of the various sections 9 is too strong, an implement may be inserted into one of the slots 8, and by a prying action the compact plate may be ejected.

If desired, instead of having the groove 10, the various sections 9 may be offset as shown in Fig. 4, so as to present a shoulder 14 beneath which the bead or projection 12 is adapted to snap when the compact plate is forced into position.

I claim:

1. A compact plate holding ring substantially L-shaped in cross section formed with a tubular body having a plurality of resilient sections, each section having a groove, said groove acting to receive part of the compact plate, and holding the same in the ring.

2. A holding ring for compact plates comprising a ring structure of L-shape in cross section, one leg of the L being resilient tubular and provided with spaced sections, each section having a groove facing inwardly, said grooves being in circumferential alignment.

3. A compact plate holding ring comprising a ring structure L-shaped in cross-section, one of the legs of the L-shaped structure presenting a resilient tubular member, said tubular member being slotted at a plurality of points for dividing the tubular member into sections, each of said sections being formed with a pressed-out portion for receiving part of the compact plate and resiliently holding the same in the ring.
- 10 4. A compact plate holding ring substantially L-shaped in cross-section, including an annular radiating flange and a tubular portion depending therefrom formed with an annular compact-receiving groove and a plurality of cuts for dividing the tubular portion into sections for increasing the resilient action of the tubular portion, said tubular portion being adapted to receive and yieldingly hold a compact plate with the entire periphery of the compact plate fitting in said groove.
